UNITED STATES PATENT OFFICE.

MATTHEW BERTRAND, OF BUTTE, MONTANA.

SELF-LAYING SUBMERSIBLE CONTACT-MINE.

1,290,054.

Specification of Letters Patent.

Patented Jan. 7, 1919.

Application filed April 10, 1918. Serial No. 227,741.

To all whom it may concern:

Be it known that I, MATTHEW BERTRAND, a citizen of the United States, residing at Butte, in the county of Silver Bow and State of Montana, have invented certain new and useful Improvements in Self-Laying Submersible Contact-Mines, of which the following is a specification, reference being had to the accompanying drawings.

10 This invention relates to floating mines, and particularly to contact mines which are exploded upon contact with a vessel or other body.

The general object of this invention is to 15 provide a mine of this character so constructed that after it is launched from a ship or other starting point it will proceed in a predetermined direction under its own power until the power of the motor is exhausted 20 or the motor ceases to function, and that the mine will automatically sink to a predetermined depth and will become automatically anchored.

A further object is to provide mines of 25 the type described with a supporting float, this float being normally held in close engagement with the mine itself, whereby the buoyancy of the float will cause the mine to be supported upon the surface of the water, 30 and provide means whereby this float is released after the mine has traveled a predetermined distance to thereby permit the mine proper to sink to an extent permitted by the cables connecting the float to the mine, 35 the mine thus being supported at a predetermined depth below the surface of the water.

A further object is to provide a mine of this character with an anchoring cable, the anchoring cable being normally wound upon 40 a suitable drum carried by the mine, and provide means whereby when the float is released, the anchor will also be released.

A further object is to provide means for 45 releasing the float and the anchor, this means being set into operation by the stoppage of the motor which normally drives the mine through the water. In other words, when the motive power gives out the mines cease to move further and the float and anchor is 50 released.

Still another object is to provide for the purpose above mentioned, a compressed air

tank, discharge from which is controlled by a valve, in turn controlled by operative connections to the motor.

55 Other objects will appear in the course of the following description.

My invention is illustrated in the accompanying drawings, wherein:

Figure 1 is an elevation showing in full 60 lines my self laying contact mine in its final position, and in dotted lines the positions taken by the contact mine before it comes to its final position;

Fig. 2 is a vertical longitudinal section 65 through the mine, the float being shown as released and the anchor as released;

Fig. 3 is a section on the line 3—3 of Fig. 2, showing the float disengaged;

Fig. 4 is a like view to Fig. 3, but showing 70 the float in place in the mine and engaged by the locking devices;

Fig. 5 is a fragmentary section on the line 5—5 of Fig. 3;

Fig. 6 is a vertical section on the line 75 6—6 of Fig. 2; and

Fig. 7 is a sectional view of the valve 32 and the cylinder 36.

Referring to these drawings, it will be seen that the body 10 of the mine is cigar-shaped having its forward end rather more pointed than its rear end and this body at its middle and upon its upper surface is formed with a downwardly extending chamber or recess 11. The ends of this recess are 80 rounded, and on the bottom of the recess are disposed the coiled expansion springs 12. Disposed forward and rearward of this recess 11 are the manholes 13, whereby access 85 may be had to the interior of the body. Extending transversely through the upper portion of the body are the flooding passages or tubes 14, which open upon the exterior of the body and into the recess or chamber 11.

95 Adapted to be disposed within this chamber 11 is the anchor float 15 which is cylindrical in form and has rounded ends. This float on its opposite side walls is formed with the recesses 16 and coacting with these recesses are bolts 17 mounted upon the upper ends of oppositely disposed levers 18, each lever being fulcrumed intermediate its ends, and each lever at its lower end being opera-

55

95

100

tively connected to a piston rod 19 carrying a piston 20 operating within a cylinder 21. It will be noted that there are four of these levers 18 and four cylinders 21, these cylinders being disposed in pairs. Each piston 20 is urged outward by a spring 22.

Each of these cylinders 21 is connected to an air line 23 which extends down to the keel of the mine and then extends longitudinally to the forward end of the mine and is there connected to a tank 24 holding compressed air. This tank may either be connected to an air pump or compressor or it may be initially filled with compressed air. It will be obvious now that if the compressed air in the tank 24 be allowed to flow to the cylinders 21, it will force the pistons 20 inward, thus releasing the bolts 17 from their engagement with the float 15. This float 15 is connected to the body of the mine by means of the anchor cable 25 and the downwardly diverging cables 26 which are connected to the walls of the recess or compartment 11. Therefore, when the float is released it will rise to the surface of the water to an extent determined by the length of the cables 25 and 26.

The mine is propelled through the water by means of a propeller 27 carried by the propeller shaft 28, in turn connected operatively to a motor 29, which I have illustrated as an internal combustion engine, though any other form of motor might be used. Coacting with this internal combustion engine is a timer 30, of any usual or ordinary form, connected in the ignition circuit of the motor by any suitable conductors. Current is supplied from a storage battery 31 from which suitable conductors return to the timer 30, these conductors being disposed in an insulating conduit.

The function of the motor 29 is not only to operate the shaft 28, but to control the valve 32 disposed in the pipe line 23, so that when the motor is operating the valve will be caused to prevent the passage of compressed air to the cylinders 21. To this end, the motor 29 drives a small air compressor 33 of any suitable form, which in turn compresses air in an air tank 34, this air tank being connected by the pipe 35 to a cylinder 36 and having therein a piston 37 operatively connected to the arm 38 of the valve 32. A spring 39 acts to urge the piston 37 in a direction to open the valve 32 but when the pressure in the cylinder 36 is sufficiently great the spring 39 is compressed and the valve 32 held closed by the pressure. Now when the motor ceases to operate, because, for instance, of the exhaustion of the storage battery 31, the spring 39 will overcome the pressure in the cylinder 36 and the valve 32 will open permitting compressed air to flow to the cylinders 21 which

will operate the releasing levers and release the float 15. As soon as the float has left the chamber or compartment 11, water will fill the space formerly occupied by the float and this will cause the mine to sink until the whole length of the cables 25 and 26 have been let out.

Where the torpedo is designed to run a considerable distance it is preferable to provide an electrically driven air compressor 75 pump 40 connected by a pipe 41 to the chamber or air tank 24, this compression pump being operated by current from a storage battery 42 connected by suitable conductors to the motor of the pump. This is not necessary, however, if the chamber 24 is initially charged with sufficient air and if there is no leakage.

The lower portion of the mine is formed to provide a chamber 43 wherein is disposed a reel or drum 44 having wound thereon a cable 45 carrying an anchor 46. This drum is held from any unwinding movement by means of a latch 47 connected to a piston rod 48, having thereon a piston 49 operating in 90 a cylinder 50 and urged in one direction by a spring 51. On the opposite side of the piston from this spring, the cylinder 50 is connected by a pipe 52 to the air pipe 23 and thus when the float 15 is released, the 95 drum or reel 44 is also released and the weight of the anchor causes the cable to unwind until the anchor touches the bottom.

The mine is normally guided by a rudder 53 which has a rudder post 54 detachably engaged by a detachable rudder shaft or pintle 54^a which is connected to a bell crank lever 55, in turn connected with a piston rod 56, entering a cylinder 57 and carrying a piston 58. A spring 59 urges the piston in 105 one direction and thus when the motor stops and the valve 32 is opened, air will pass by means of pipe 60 to the cylinder 57 forcing the piston 59 back and lifting the pintle 54^a from its engagement with the rudder, thus 110 detaching the rudder automatically. Preferably the rudder is connected by a cable 61 to a weight 62, this cable 61 being preferably about one hundred and fifty feet in length.

The body 10 is formed to provide an elongated compartment within which the operating mechanism heretofore described is disposed, and exteriorly of this compartment, that is between it and the outer shell of the 120 mine, is placed gun cotton or other high explosive. The explosive charge, which may be of gun cotton or any other suitable material, may be disposed in any suitable chamber or compartment in the mine and I do not 125 wish to be limited to any particular disposition for this explosive charge, but I have illustrated the mine as being formed with a belt of gun cotton a disposed in a suitable compartment formed upon the exterior of 130

the shell 10 of the mine and extending longitudinally thereof on each side of the mine. Any suitable means may be used for igniting the explosive charge of the mine and I 5 do not wish to limit myself to the use of any particular detonating means. I have shown for this purpose, however, a series of contact pins 63 which extend through tubes 64 and which are urged upward by springs 65 and 10 the inner end of each pin engages with a contact member 66 normally held out of electrical engagement with a coacting contact member 67. These contact members 66 and 67 are electrically connected by suitable 15 wiring 68 to dry batteries 69, though other forms of batteries may be used. It is obvious that when a vessel strikes this mine one or more of the contact pins 63 will be forced inward, thus closing an electrical circuit. 20 This electrical circuit may include in it any suitable detonating device whereby the charge may be exploded. I have not attempted to show the detonating device, however, as this forms no part of my invention. 25 Any other suitable means may be used to secure the explosion of the mine upon contact with a vessel.

The general operation of this mechanism will be obvious from what has gone before. 30 When the mine is launched, the float 15 is disposed within the compartment 11 so that the float 15 supports the mine on the surface of the water. Under these circumstances, the propeller will act to drive the mine a 35 predetermined distance, as for instance the length of the cable 61 and the rudder will cause the mine to proceed in a predetermined direction. When the mine has shifted to the full length of the cable, the mine, 40 if the weight is heavy enough, will be held from further forward movement, but if on the other hand, the weight is relatively light, the mine will continue to move forward dragging the weight after it, until 45 the motor ceases to operate.

The motor will continue to act until it is either stopped by lack of fuel, the exhaustion of its storage batteries, or from any other predetermined cause, and then the 50 valve 32 will open, permitting compressed air to pass from the reservoir 24 into the latch releasing cylinders 21, causing the release of the latches 17 and permitting the float to rise to the surface of the water. 55 At the same time that the float is released, the latch 47 is released from its engagement with the drum permitting the anchor to drop. At the same time, the rudder is detached and drops off. 60 The reason for detaching the rudder is twofold. After the mine has reached its predetermined position, there is no further use for the rudder, and the connection of the mine to the weight would prevent the 65 mine from swinging properly with the cur-

rent, which is obviated by detaching the rudder. Further, the detachment of the rudder prevents the mine being afterward used by enemies. It will be obvious, of course, that the weight, if the mine drags 70 the weight after it, will hold the rudder in a straight line and guide the mine. The weight 62 is attached to the rudder to keep the rudder straight when the mine is in motion and to sink the rudder when detached. 75 A further reason for detaching the rudder is to cause the mine to balance when it comes to a stop. If the rudder were not detached, the weight and rudder would cause the mine to tilt upward with the bow higher than the stern. 80

After the float has been released, the anchor released and the rudder weight released, the mine will be supported a predetermined distance below the surface of the 85 water and anchored from further movement.

While I have illustrated a form of my invention which I believe to be particularly effective, it will be understood that many minor changes may be made in the details of 90 construction and the arrangement of the parts without departing from the spirit of the invention, as defined in the appended claims.

Having described my invention, what I 95 claim is:

1. A mine, propelling mechanism therefor, including a motor, means for supplying power to the motor for a predetermined time, a float having flexible connections to 100 the mine, means for holding the float in close engagement with the mine to thereby cause the flotation of the mine, and means for releasing the float from direct engagement with the mine when the motive power has 105 become exhausted, to thereby permit the mine to sink.

2. A mine, propelling mechanism therefor including a motor, means for causing the stoppage of the motor after a predetermined 110 time, a float having flexible connection with the mine, means for holding the float in close engagement with the mine, and means operated upon the stoppage of the motor releasing the float from its engagement with 115 the mine, to thereby permit the mine to sink a distance equal to the length of the connection between the float and the mine.

3. A mine, propelling mechanism therefor including a motor, means causing the 120 stoppage of the motor after a predetermined time, anchoring means normally held in inoperative position, a float normally held in closed engagement with the mine to thereby cause its flotation, and means operated by 125 the stoppage of the motor for releasing said float and releasing said anchoring means.

4. A mine, means for propelling the mine for a predetermined time, means for supporting the mine upon the surface of the 130

- water while it is being propelled, and means causing the mine to sink to a predetermined distance below the surface of the water upon the stoppage of the propelling means.
5. A mine, propelling mechanism therefor including a motor, and means causing the motor to function for a predetermined time, a rudder, and means operated upon the stoppage of the motor causing the mine to sink a predetermined distance and releasing the rudder from its engagement with the mine.
10. A mine, propelling mechanism therefor including a motor, means for causing the motor to operate for a predetermined time, a reel carried on the mine, an anchoring cable connected thereto and normally wound thereon, and means operated upon a stoppage of the motor causing the mine to sink to a predetermined level and releasing said reel to permit the anchor to be released.
15. A mine, propelling mechanism therefor including a motor, means for supplying power to the motor for a predetermined time, a detachable rudder and an anchoring weight and length of flexible connection between said weight and the rudder, and means for causing the sinking of the mine to a predetermined level upon the exhaustion of the motive power and for releasing said rudder from its engagement with the mine upon said exhaustion.
20. A mine having an upwardly opening chamber, a float normally disposed in said chamber, latches mounted within the mine and having portions thereof engaging directly with the float, and holding the float in place in the chamber, and means acting upon a predetermined lapse of time releasing said latches, the mine being flexibly connected to the float and being heavier than water.
25. A mine, a float therefor, latches holding the float in engagement with the mine, flexible connections between the float and the mine, cylinders, pistons connected to the latches and disposed within the cylinders, springs holding the latches in engagement with the float, a pipe connected to a source of compressed air and extending to the said cylinders, a valve normally closing passage through the pipe, and means operating after
30. a predetermined lapse of time acting to open the valve and permit the delivery of compressed air into the cylinders thereby causing the release of the latches.
35. A mine, a float therefor, flexible connections between the float and the mine, a motor, propelling mechanism connected to the motor, and motor controlled means for holding the float in close engagement with the mine.
40. A mine having an upwardly opening compartment, a float normally disposed in said compartment, this compartment being connected to flooding tubes opening upon the outside of the mine, flexible connections between the mine and the float, means for retaining the float within said compartment, and motor controlled means for releasing said float.
45. A mine having an upwardly opening compartment, a float normally disposed in said compartment, the compartment being connected to flooding tubes opening upon the outside of the mine, flexible connections between the mine and the float, means for retaining the float within said compartment, springs urging the float out of the compartment, and motor controlled means for releasing said latches.
50. A mine, propelling means therefor including an internal combustion motor, storage batteries electrically connected to the ignition system of the motor, a float receiving compartment, a float therein having flexible connections to the mine, means for retaining the float in close engagement with the mine including spring actuated latches, compressed air operated means for releasing said latches, an air tank, a tubular connection from the air tank to the compressed-air operated means, a valve controlling the flow of air, and motor controlled means for opening said valve upon the stoppage of the motor.
55. In testimony whereof I hereunto affix my signature in the presence of two witnesses.
60. MATTHEW BERTRAND.
